CLAIM

The ornamental design of a dental tip, as shown and described.

DESCRIPTION

FIG. 1 is a top perspective view of a dental tip wherein my new design is embodied in a nozzle;

FIG. 2 is a left side elevational view thereof, the right side being a mirror image;

FIG. 3 is a top plan view thereof;

FIG. 4 is a bottom plan view thereof;

FIG. 5 is a rear elevational view thereof;

FIG. 6 is a front elevational view thereof;
FIG. 7 is a rear elevational view thereof, shown in an open position;

FIG. 8 is a top perspective view of a second embodiment thereof, wherein my design is embodied in a combined nozzle and cap therefor;

FIG. 9 is a left side elevational view of the embodiment of FIG. 8, the right side being a mirror image;

FIG. 10 is a top plan view of the embodiment of FIG. 8;

FIG. 11 is a bottom plan view of the embodiment of FIG. 8;

FIG. 12 is a rear elevational view of the embodiment of FIG. 8;

FIG. 13 is a front elevational view of the embodiment of FIG. 8;

FIG. 14 is a rear elevational view of the embodiment of FIG. 8, shown in an open position;

FIG. 15 is a top perspective view of a third embodiment thereof, wherein my design is embodied in a nozzle;

FIG. 16 is a left side elevational view of the embodiment of FIG. 15, the right side being a mirror image;

FIG. 17 is a top plan view of the embodiment of FIG. 15, the bottom being identical in appearance;

FIG. 18 is a front elevational view of the embodiment of FIG. 15;

FIG. 19 is a rear elevational view of the embodiment of FIG. 15;

FIG. 20 is a rear elevational view of the embodiment of FIG. 15, shown in an open position;

FIG. 21 is a top perspective view of a fourth embodiment thereof, wherein my design is embodied in a nozzle;

FIG. 22 is a left side elevational view of the embodiment of FIG. 21, the right side being a mirror image;

FIG. 23 is a top plan view of the embodiment of FIG. 21, the bottom being identical in appearance;

FIG. 24 is a front elevational view of the embodiment of FIG. 21;

FIG. 25 is a rear elevational view of the embodiment of FIG. 21;

FIG. 26 is a rear elevational view of the embodiment of FIG. 21, shown in an open position; and

FIG. 27 is a reduced top perspective view of a fifth embodiment thereof, wherein my design is embodied in a combined nozzle and cap therefor, the only difference residing in the inclusions of a cap element.
